Attn: J.S.

UNITED STATES PATENT OFFICE

136,961

DESIGN FOR AN OIL FILTER CASING

Eric Siemers, Kalamazoo, Mich., assignor to Roscoe B. Lacey, Kalamazoo, Mich.

Application September 18, 1943, Serial No. 111,156

Term of patent 7 years

To all whom it may concern:

Be it known that I, Eric Siemers, a citizen of the United States, residing at Kalamazoo, in the county of Kalamazoo and State of Michigan, have invented a new, original, and ornamental Design for an Oil Filter Casing, of which the following is a specification, reference being had to the accompanying drawing, forming part thereof.

In the drawing:

I claim:

The ornamental design for an oil filter casing, as shown.

ERIC SIEMERS.
